US00D904090S

(12) **United States Design Patent** (10) Patent No.: **US D904,090 S**
(45) Date of Patent: **** Dec. 8, 2020**

(54) **PRODUCT RETAINER**

- (71) Applicant: **Apple Inc.**, Cupertino, CA (US)
(72) Inventors: **Sheng Yang**, Mountain View, CA (US);
Ricardo A. Mariano, Hayward, CA (US); **Allison Inouye**, San Francisco, CA (US); **Kristy Judy Hsu**, San Jose, CA (US); **Po Huang**, San Jose, CA (US); **Jean-Marc Gady**, Los Altos, CA (US); **Peter Russell-Clarke**, San Francisco, CA (US); **Daniele De Iuliis**, San Francisco, CA (US); **Rico Zörkendorfer**, San Francisco, CA (US); **Molly Anderson**, San Francisco, CA (US); **Jody Akana**, San Francisco, CA (US)
(73) Assignee: **Apple Inc.**, Cupertino, CA (US)
(**) Term: **15 Years**
(21) Appl. No.: **29/743,202**
(22) Filed: **Jul. 20, 2020**

Related U.S. Application Data

- (63) Continuation of application No. 29/695,817, filed on Jun. 21, 2019, now Pat. No. Des. 893,926.

(57) **CLAIM**

The ornamental design for a product retainer, as shown and described.

DESCRIPTION

FIG. 1 is a top front perspective view of a product retainer showing the claimed design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a top front perspective view thereof showing the claimed design in an environment in which it may be used; and,
FIG. 9 is a bottom rear perspective view thereof.
The broken lines in the figures show portions of the product retainer and environment that form no part of the claimed design.

1 Claim, 7 Drawing Sheets
